US0D1068798S

(12) **United States Design Patent** (10) **Patent No.:** **US D1,068,798 S**
Craven (45) **Date of Patent:** **** Apr. 1, 2025**

(54) **DISPLAY SCREEN OR PORTION THEREOF
WITH A GRAPHICAL USER INTERFACE**

(71) Applicant: **Meta Platforms, Inc.**, Menlo Park, CA (US)

(72) Inventor: **Timothy Jordan Craven**, Vancouver, WA (US)

(73) Assignee: **Meta Platforms, Inc.**, Menlo Park, CA (US)

(**) Term: **15 Years**

(21) Appl. No.: **29/869,014**

(22) Filed: **Dec. 19, 2022**

(51) **LOC (15) Cl.** **14-04**

(52) **U.S. Cl.**

USPC **D14/485**

(57) **CLAIM**

The ornamental design for a display screen or portion thereof with a graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

The FIGURE is a front view of a of a display screen or portion thereof with a graphical user interface.

The dashed broken lines depict portions of the display screen or portion thereof with a graphical user interface which form no part of the claimed design. The dot-dashed broken lines represent boundaries of the claimed display screen or portion thereof with a graphical user interface and form no part of the claimed design.

1 Claim, 1 Drawing Sheet
